CLAIM

The ornamental design for a board game, as shown and described.

DESCRIPTION

FIG. 1 is a top plan view of the board game, showing my new design, the broken line showing of the indicia is for illustrative purposes only, and forms no part of the claimed design;

FIG. 2 is a front elevational view, thereof;

FIG. 3 is a right side elevational view, thereof;

FIG. 4 is a rear elevational view, thereof;

FIG. 5 is a left side elevational view, thereof;

FIG. 6 is a perspective view thereof; and,

FIG. 7 is a top plan view of a second embodiment of a board game.

The broken line showing of the playing pieces in FIGS. 2-6 is for illustrative purposes only and forms no part of the claimed design.

FIG. 1

FIG. 2

FIG. 3

FIG. 4

FIG. 5

FIG. 7
